Primary Examiner — Samantha Q Lawrence*Assistant Examiner* — Kimberly Barnes(74) *Attorney, Agent, or Firm* — Grossman Tucker Perreault & Pfleger, PLLC(57) **CLAIM**

We claim the ornamental design for a vacuum body for a vacuum cleaner, as shown and described.

DESCRIPTION

FIG. 1 is a front, top, left perspective view of a vacuum body for a vacuum cleaner, showing a new design;

FIG. 2 is a front, top, right perspective view thereof; and, FIG. 3 is a rear, top, right perspective view thereof.

Broken lines in the drawings are for the purpose of illustrating portions of the vacuum cleaner that form no part of the claimed design.
